Primary Examiner — Sharon S Oum(74) *Attorney, Agent, or Firm* — McGarry Bair PC(57) **CLAIM**

The ornamental design for a ceiling fan cage as shown and described.

DESCRIPTION

FIG. 1 is a top perspective view of a ceiling fan cage, shown in the environment of a ceiling fan, showing our new design. FIG. 2 is a bottom perspective thereof, having the ceiling fan environment removed;

FIG. 3 is a top view thereof;

FIG. 4 is a bottom view thereof;

FIG. 5 is a front view thereof, with the rear view being identical thereto; and,

FIG. 6 is a right-side view thereof; with the left-side view being identical thereto.

Portions of the ceiling fan and ceiling fan environment shown in broken lines form no part of the claimed design.

1 Claim, 6 Drawing Sheets(56)
